UNITED STATES PATENT OFFICE.

WILLIAM S. HARRINGTON AND GUSTAV E. OFF, OF KEOKUK, IOWA.

DESIGN FOR A RIGHT-OF-WAY INDICATOR.

Application filed November 14, 1925. Serial No. 15,425. Term of patent 3½ years.

To all whom it may concern:

Be it known that we, WILLIAM S. HARRINGTON and GUSTAV E. OFF, citizens of the United States, residing at Keokuk, in the county of Lee and State of Iowa, have invented a new, original, and ornamental Design for Right-of-Way Indicators, of which the following is a specification, reference being had to the accompanying drawing, forming part thereof.

Fig. 1 is a front elevational view of a right-of-way indicator showing our new design.

Fig. 2 is an end elevational view looking from the left hand of Fig. 1.

We claim:

The ornamental design for a right-of-way indicator, as shown.

WILLIAM S. HARRINGTON.
GUSTAV E. OFF.
